UNITED STATES PATENT OFFICE.

CORODEN J. SLAFTER, OF GRAND JUNCTION, MICHIGAN.

LANTERN DINNER-PAIL.

SPECIFICATION forming part of Letters Patent No. 270,610, dated January 16, 1883.

Application filed June 2, 1882. (No model.)

To all whom it may concern:

Be it known that I, CORODEN J. SLAFTER, a citizen of the United States, residing at Grand Junction, county of Van Buren, State of Michigan, have invented a new and useful Lantern Dinner-Pail, of which the following is a specification.

The object of my invention is to construct a device which may be used as a dinner-pail and a lantern, and by means of which the food and drink may be kept warm.

It consists of a pail having a food and a lantern compartment, and a can for holding liquid detachably connected or located on top, and a lamp internally located.

In the drawings, forming a part of this specification, Figure 1 is a perspective view showing the food-compartment; Fig. 2, a perspective view showing the lantern-compartment opposite; Fig. 3, top perspective with liquid-can removed; Fig. 4, section on line 3 3 in Fig. 2 and line 1 2 in Fig. 5, and Fig. 5 a cross-section on line 4 4 in Fig. 4.

The pail proper is composed of a frame consisting of the two side supports, B B, oblique partitions F F, the semicircular open center tube, v v, and sliding door D', said frame being provided with a top and bottom inclosure. The sliding door D' is located in recessed flanges i i, extending downward and upward from the circular edge of the top and bottom of the pail, respectively. In the center of the bottom, communicating with the lower end of tube v, is a recess for lamp L, the chimney h of which is located in the open tube v. The upper end of tube v, Fig. 3, communicates with a recess, t, of the liquid-can D. This recess or center opening is oblong in shape, and receives the handle e of the pail, thus keeping said can detachably in place. f is a closed orifice to can D, in which, by removing the stopper, may be placed the liquid for drink, such as coffee, &c.

C is an inclined plate, which, together with the oblique partitions F F, forms reflectors to the light, Fig. 2.

a a are shelves to the food-compartment. They slide into recesses c' c' and 7 7, Figs. 4 and 5. The use and arrangement of the shelves are shown in Fig. 1. In this figure door D' is in the location shown in Fig. 5. In Fig. 2 the door is in position to close the food-compartment and open the lantern part.

It will be readily seen that with a device thus constructed and arranged the food and drink may be easily carried, kept warm, thus obviating freezing in cold weather, and it can be used as a lantern to light the laborer home, thus obviating the need of carrying two devices.

Having thus described my invention, what I claim as new and desire to secure is—

1. In a lantern dinner-pail, the two side supports, the oblique partitions, the central semicircular open tube, a top and bottom inclosure, the sliding door, and the detachable shelves, all combined substantially as described.

2. The lantern dinner-pail composed of the side supports, the oblique partitions, central open tube, top and bottom inclosures having the recessed flanges adapted to receive the sliding door, the door, the handle, and lamp, all substantially as specified and shown.

3. The combination, with the pail having the handle secured to the upper end, of a can having the oblong central orifice receiving said handle, which detachably holds said can on the pail, substantially as set forth.

CORODEN J. SLAFTER.

Witnesses:

JOHN H. CHASE,
BELLE A. SLAFTER.
